UNITED STATES PATENT OFFICE.

RAY KEEN, OF ELLENSBURG, WASHINGTON.

MAP HOLDER.

Application filed September 1, 1926. Serial No. 133,044.

- This invention relates to holders for use in the operation of strip maps contemplating the provision of a housing having manually and simultaneously operable spools therein 5 for traveling appropriate portions thereof over a bridge plate positioned immediately behind a sight opening provided in the face of the housing to permit reading of the exposed portions of the map.
- 10 With the above and other objects in view the invention further includes the following novel features and details of construction to be hereinafter more fully described, illustrated in the accompanying drawing and 15 pointed out in the appended claims.

In the drawing:

Figure 1 is a perspective view of the invention;

Figure 2 is a vertical view thereof;

20 Figure 3 is a transverse section taken through one of the spools and illustrating the construction thereof.

Figure 4 is a diagrammatic plan view of a spool and tab end of the strip map.

25 Figure 5 is a horizontal section taken through a spool and illustrating the manner by means of which the tab end of the strip map is securely held thereon.

Referring to the drawing in detail wherein 30 like characters of reference denote respective parts, the reference character 10 indicates the back of a housing having the forward portion of the housing consisting of a cover plate 11 hingedly secured upon its lower edge while 35 their respective and opposite ends are being held against accidental displacement by an off set spring finger 11 arranged upon the inner side of the back plate 10 and having its free end crimped or bent upon itself and fitted 40 within a depressed portion arranged upon the inner side and adjacent the top of the cover plate 11. A relative large sight opening 12 being provided within the face of the cover plate 11 and immediately behind the 45 same and in slight spaced relation thereto is a bridge plate 13 having its respective end portions rolled as indicated at 14, the purpose of which will be readily apparent.

Cross section rectangular shaped sleeve 50 members 15, of which may be properly termed spools, receive axles or shafts 16 therein for journaling the same within the opposite side walls of the cover plate 11 and provided with knobs or dials 17 upon their 55 corresponding ends in order that the spools may be imparted a rotary movement upon

the simultaneous operation of the knobs 17. The axles 16 having reduced portions 18 provided at intermediate points in their lengths and within which are received and tensioned 60 the ends of spring fingers 19 struck from the sleeves or spools 15. A strip map such as indicated at 21 having appropriate portions thereof wrapped upon the spools or sleeves 16 and adapted to expose appropriate portions 65 of its length to the sight opening 12 and upon the face of the bridge plate 13, in the manner as illustrated in Figure 2 of the drawing. The opposite end portions of the strip map 20 are provided with tabs 21 fitted within elongated slots in the sleeves or spools 15 beneath the axle 16 and held against displacement by 70 the spring fingers 19 carried by the sleeve.

It will be noted from the foregoing description and accompanying drawing that 75 the invention provides an exceedingly useful and advantageous strip map holder which owing to the provision of a securing hook or clamp 23 provided upon the rear side of the plate 10 which may be fitted upon an appropriate portion of a motor vehicle within convenient reach of the operator in order that portions of the map may be read, the knobs 17 rotated an appreciable distance to expose other portions of the map. The map 80 upon the strip being so arranged as to provide ample and sufficient space upon the opposite sides thereof to permit the jotting down of expenditures distances, upon the strip and which may be readily added to ascertain the 85 entire course or expenditure of the trip as a whole or between certain designated points.

The invention is susceptible of various changes in its form provisions and minor details, of construction, and the right is herein reserved to make such changes which properly fall within the scope of the appended 90 claims.

Having thus described my invention what is claimed is:

1. A map holder comprising a housing having a sight opening in the face thereof, spools of substantial rectangular cross section having spring fingers struck therefrom at appropriate points in their lengths, axles 105 extended within the spools and provided with reduced portions at appropriate points in their lengths and within which are tensioned the free ends of the spring fingers, said spools having slotted portions, and a strip 110 map having tab portions received within the slots in the walls of the spools and upon

which is tensioned the opposite sides of the axles to retain the map against accidental displacement within the housing.

2. In a map holder, a housing having a strip map movable therein and a winding spool to receive the strip, said spool comprising a hollow shank and having an operating knob thereon, an annular groove within the axle, and a spring finger carried by the shank and extended within the groove to provide an interlocking connection between the shank and axle.
3. In a map holder, a housing having a

strip map movable therein and a winding spool to receive the strip, said spool comprising a hollow shank having oppositely located slots to receive one end of the strip, an axle extending through the shank and bearing upon the strip, and means adapted to provide an interlocking connection between the axle and shank to clamp the strip between the axle and shank to hold the strip in position.

In testimony whereof I affix my signature.
